UNITED STATES PATENT OFFICE.

HENRY W. SUMNER, OF SEATTLE, WASHINGTON.

STARTING-IGNITER FOR INTERNAL-COMBUSTION ENGINES.

1,361,116.

Specification of Letters Patent.

Patented Dec. 7, 1920.

Application filed July 3, 1918. Serial No. 243,212.

To all whom it may concern:

Be it known that I, HENRY W. SUMNER, a citizen of the United States, and resident of the city of Seattle, county of King, and 5 State of Washington, have invented certain new and useful Improvements in Starting-Igniters for Internal-Combustion Engines, of which the following is a specification.

My invention relates to internal combustion engines of the surface ignition type and 10 consists of a means for igniting the charges at starting.

The object of my invention is to provide an improved device for use in igniting the 15 charges in internal combustion engines of the class described, which device may be used when starting an engine to insure prompt and certain ignition, until the heat generated by the burning of the charges, 20 has heated up the normal igniting surfaces to a sufficient temperature to ignite the charges.

Another object of my invention is to provide a device of this character in a design 25 wherein the parts thereof which are essential to its proper operation, shall when in use be exposed as little as possible to the heat generated by the combustion of the charges, and wherein, when not in use, all the essential 30 parts shall be protected from the heat of combustion of the charges.

Another object is to provide a construction 35 wherein the igniting device may be removed from and replaced in the engine while the engine is running using its normal surface ignition.

The construction and operation of my invention will be hereinafter described, as it 40 has been embodied in the form which is now preferred by me, and that which I consider novel and upon which I desire patent, will be defined in the claims.

The drawing is a section through the combustion chamber and the adjacent end of 45 an engine cylinder showing my invention applied thereto.

In that class of internal combustion engines employing surface ignition, or in which the ignition of the charge is secured 50 by the heat of the walls of a combustion chamber, or of some other member which is exposed to and heated by the heat of the charge, it is necessary, in starting, to provide means, either for preliminary heating of 55 this member, or for independently thereof

igniting a sufficient number of charges to heat up the igniting member.

In the drawing, 1 represents a combustion and compression chamber which is secured to and communicates with the end of an engine cylinder 2. The piston has not been shown. These, as herein shown and described, are only illustrative of the type of engine with which my device is intended to work. My device may be employed with 65 any standard construction of these parts.

At a convenient point, preferably where it will be subjected to the fuel spray issuing from the nozzle 10, I provide a bore or chamber 3, which communicates with the combustion chamber and forms an ignition chamber. In this I provide an ignition member and also means for sealing or cutting off this ignition chamber from the combustion chamber.

As I prefer to construct these parts, the ignition chamber is divided into two parts, a bore 30 which receives the valve by which the ignition chamber is sealed, and the bore 31 in which the ignition member 80 is placed.

The bore 30 has a valve seat 32, somewhat inward from its inner end, or that end which connects with the combustion chamber, and facing outwardly, or away from the combustion chamber. The valve 4, has a tip 40 which fills the inner mouth of the bore 30 and a valve surface 41 which seats upon the valve seat 32.

The valve 4 is connected with a hand 90 wheel 5 in some manner which permits easy reciprocation thereof, as by a threaded stem 50 which is connected therewith. Any suitable means for operating the valve may be used. As shown, the stem is connected with the valve by a rotative joint consisting of a head 51 on the stem which enters a T-slot in the valve.

The bore 31 in which the ignition member is placed, connects with the bore 30 outwardly of but close to the valve seat 32. This ignition member is constructed as a plug which may be inserted and removed as necessary. When the valve 4 is seated the ignition plug may be removed, even if the 105 engine is running.

The plug shown employs a body 6, which screws into the bore. This has its inner end provided with a marginal tapering zone 60, which seats upon a complementary shoulder 110

in the bore, to thereby make a tight joint. I have also shown the greater part of the body of the plug as of such reduced diameter as to leave a shallow chamber 61 surrounding it and forming a heat insulating means.

This plug is centrally bored, and in this bore is a rod 7, of smaller diameter than the bore and having a head 70, between which 10 and the inner end of the body 6 is placed a washer 62 of electrically insulating material. The end of the body 6 is recessed to receive this washer, thereby securing the stem 7 in exact concentric position in the 15 body of the plug. A similar washer is similarly recessed in the outer end of the body of the plug. These washers hold the stem 7 out of electrical contact with the body 6. A nut 71 secures the whole together.

20 An extension 72 at the outer end of this stem forms one member of an electrical connection, of which the socket 73 is the other. The inclosing or sleeve cylinder 74 is an insulator.

25 Supported upon the inner projecting end of the stem 7 is a wire 8, which has one end connected with the stem 7 and its other end connected with the body 6. This wire is so proportioned to the electrical current 30 to be used, that it will be thereby heated to a temperature which will promptly ignite a combustible mixture which may be brought into contact therewith.

To make absolutely certain that the combustible mixture being compressed in the combustion chamber 1 be brought into igniting relation with the igniting member contained in the chamber 31, I may provide a bleed or snifter port to permit a slight discharge therefrom, thus insuring the drawing 40 therein of the fuel and its ignition. I have shown such a port at 9. As shown, this is continued as a central bore in the bolt 90, and if its action is found unnecessary, 45 it may be closed by substituting a bolt which is not bored.

With the engine running under normal conditions, the valve 4 is closed and the electrical connection with the ignition plug 50 is removed. In this condition the valve seating surfaces 41 and 32, are protected from the direct action of the heat and the gases of combustion, by the tip 40 of the valve, which tip fills the mouth of the opening. With the valve closed the ignition plug 55 may be removed.

By keeping the igniting member of the starting plug removed from free and open exposure to the heat of combustion in the 60 combustion chamber 1, excessive heating thereof and its consequent burning out is prevented.

65 By making the seating of the valve so that the valve is withdrawn from the combustion chamber in opening, instead of being

projected into the combustion chamber, this valve and its seat is protected from excessive heating and its life is further contributed to by using the tip 40 which protects the seats when the valve is closed.

When it is desired to start the engine, the valve may be withdrawn, thus connecting the ignition chamber and its ignition member 8, with the combustion chamber 1. Connecting the electric feed wire with the ignition plug, the wire 8 will be heated so that it will ignite the charges, and this may continue until the walls of the combustion chamber are sufficiently heated to ignite the charge. Where a fairly high compression 80 is used this need not be for a very long period.

The making of the ignition plug separate from the valve and locating it in a bore which is closed off from the combustion 85 chamber by the valve, enables removal of the ignition plug while the engine is running.

Locating the ignition member back in a recess out of the combustion chamber, 90 protects it from the heat of the burning charge. With this heat added to the heat produced by the electric current, it is apt to be soon burned out. At the same time, the ignition of the charge is as reliably secured.

95 Placing the valve seating surfaces back in the recess also protects them from the continued action of the burning charges, and they are not injured thereby and the life of the valve is prolonged.

100 What I claim as my invention is:

1. In combination, a combustion chamber having an ignition-plug-receiving chamber, a priming ignition plug adapted to be secured in said chamber with its igniting element back from the opening thereof, and means independent of said ignition plug manually operable to control said opening.

2. A device as in claim 1 in which the chamber has two branches, one of which 110 has therein the means for closing the opening of the chamber and the other the ignition plug.

3. A device as in claim 1 in which the igniting element is maintained in fixed position and the closing means employs a valve closing the opening by movement toward the combustion chamber.

4. In combination, a combustion chamber having a valve receiving bore extending to 120 the exterior and containing an outwardly facing valve seat, and also having an ignition-plug-receiving bore intersecting the first bore outwardly of said valve seat, a valve insertible in the first bore and a priming ignition plug insertible in said second bore.

5. In combination, a combustion chamber having a valve receiving bore extending to 130 the exterior and containing an outwardly

facing valve seat, and also having an ignition-plug-receiving bore intersecting the first bore outwardly of said valve seat, a valve insertible in the first bore having a tip extending inward beyond the seat thereof and substantially filling the mouth of its receiving bore, and an ignition plug insertible in said second bore.

6. In combination, a combustion chamber, an igniting chamber connected with the combustion chamber, a valve adapted to close the connection between the ignition chamber and the combustion chamber, said valve being mounted to withdraw its seating surface from the combustion chamber in opening, and a priming ignition member independent of the valve and located in said chamber beyond the valve seat from the combustion chamber.

10 7. In combination, a combustion chamber, an igniting chamber connected therewith and having a valve seat located back from the combustion chamber, an ignition plug insertible into said ignition chamber outwardly of said valve seat, a valve adapted to engage said seat and having a tip which, when the valve is seated, fills the neck of the ignition chamber between the valve seat and the inner surface of the combustion chamber.

15 8. An igniting device for internal combustion engines comprising a priming igni-

tion member and means separate therefrom adapted to seal the ignition member from the combustion chamber.

9. In combination, a combustion chamber and an ignition chamber connecting therewith, an ignition member in said ignition chamber back from the combustion chamber, said ignition chamber being provided with a sniffer port.

10. In combination, a combustion chamber having an ignition chamber connecting therewith and having a sniffer port, an igniting member located at all times back in the ignition chamber, and a valve independent of the ignition member adapted to close the connection between the ignition chamber and the combustion chamber.

11. In combination, a combustion chamber and an ignition chamber connected with the combustion chamber, said ignition chamber having a permanently open sniffer port connecting therewith.

12. In combination, a combustion chamber and an ignition chamber connected with the combustion chamber, said ignition chamber having a permanently open sniffer port connecting therewith, and a valve adapted to close the connection between ignition and combustion chambers.

Signed at Seattle, Washington.

HENRY W. SUMNER.
